UNITED STATES PATENT OFFICE.

BENJAMIN F. BECKWITH, JAMES B. BECKWITH, AND JOSEPH BURSON, OF PLUM HOLLOW, IOWA.

ANTI-FREEZING BOX FOR TURBINE SHAFTS.

SPECIFICATION forming part of Letters Patent No. 339,730, dated April 13, 1886.

Application filed December 30, 1885. Serial No. 187,073. (No model.)

To all whom it may concern:

Be it known that we, BENJAMIN F. BECKWITH, JAMES B. BECKWITH, and JOSEPH BURSON, all of Plum Hollow, in the county of Fremont and State of Iowa, have invented certain new and useful Improvements in Anti-Freezing Boxes for Turbine Shafts; and we do hereby declare that the following is a full, clear, and exact description of the invention, which will enable others skilled in the art to which it appertains to make and use the same, reference being had to the accompanying drawings, which form a part of this specification, and in which—

15 Figure 1 is a perspective view of as much of a turbine water-wheel and of its frame as is necessary to illustrate our invention; and Fig. 2 is a longitudinal vertical section of the same.

20 Similar letters of reference indicate corresponding parts in both the figures.

Our invention has relation to packing-boxes for the shafts of turbine water-wheels; and it consists in the improved construction and 25 combination of parts, as hereinafter more fully described and claimed.

In the accompanying drawings, the letter A indicates a portion of the top of the turbine wheel, and B is the vertical shaft of the same. 30 The upper end of this shaft is passed through a cross-timber, C, to the lower side of which is secured a flange, D, upon the upper end of a tube, E, which surrounds the shaft and extends from below the depth in the water at 35 which it will freeze to above the surface of the water. The lower end of the tube E is enlarged to form a packing-box, F, of greater exterior diameter than the tube itself, and having a packing, G, of any suitable material, 40 placed within it, and the reduced upper end of sleeve H of a cap, I, fits up within the lower portion of the packing-box F on the lower end of the tube B, and compresses the packing G, the cap being secured adjustably 45 in operative position by means of bolts J, passing through vertical apertures in the enlarged portion of the cap I and the enlarged portion of the lower end of the tube E, as shown, and by means of the nuts J' on the ends of these

bolts the reduced portion of the cap I may be 50 drawn more or less closely up into the enlarged lower end of the tube E, so as to thoroughly compress the packing G, as the latter becomes worn around the shaft B by the revolution of the shaft, thereby preventing any 55 leakage of the oil or fluid surrounding the shaft above the said packing, as will be readily understood.

The tube is filled with a fluid which will not freeze, and which at the same time may 60 serve as a lubricant; and it will thus be seen that the shaft will be free to turn within the tube at all times, the unprotected portion of the shaft being below the point in the water at which it freezes, and the upper portion of 65 the shaft being surrounded by the fluid, which will not freeze, and which fluid is prevented from escaping at the lower end of the tube by the packing-box.

This device may be used for other shafts 70 which are operated under water, the tube in all cases extending from above the surface of the water to a depth at which the water will not be liable to freeze; and in this manner such shafts may be operated during the entire 75 winter as long time as water is able to flow under the ice for driving the turbine wheel, without the necessity of chopping the ice away from the shaft, so that it may revolve at each time the shaft has been stopped a sufficient 80 length of time to allow the water to freeze around it.

Glycerine or some non-freezing lubricant is the most preferable fluid to use in the tube, although oil may be used, as it will not freeze 85 as hard as ice, and will easily be thawed as soon as the shaft is revolved within it and a slight heat created, when it will be sufficiently soft not to interfere with the revolutions of the shaft, and also be sufficiently soft to lubricate the shaft in the packing-box.

Having thus described our invention, we claim and desire to secure by Letters Patent of the United States—

The combination of a turbine water-wheel 95 shaft, a tube having a flange at its upper end and secured by the said flange to a cross-beam above the water, and having its lower end en-

larged to form a packing-box of greater exterior diameter than the tube proper, suitable packing in the said box, a cap having its sleeve entering the box from the under side
5 and having an enlarged outer portion, and bolts having nuts and passing through the enlarged portions of the packing-box and of the cap, said packing-box and cap being above the wheel and the lower bearings of the shaft,
10 the tube being filled with a non-freezing fluid, as and for the purpose shown and set forth.

In testimony that we claim the foregoing as our own we have hereunto affixed our signatures in presence of two witnesses.

BENJAMIN F. BECKWITH.
JAMES B. BECKWITH.
JOSEPH BURSON.
